CLAIM

(52) U.S. Cl.

The ornamental design for a fuel cartridge, as shown and described.

USPC ..... **D27/161****DESCRIPTION**(58) **Field of Classification Search**

FIG. 1 is a top front perspective view of a fuel cartridge employing an ornamental design in accordance with the present invention.

USPC D27/100–112, 120, 125–130, 136, 137,
D27/138, 143, 161, 162–169, 172, 175,
D27/180, 183, 193, 194, 195; D3/228,
D3/229; D23/332, 341

FIG. 2 illustrates a front view of the fuel cartridge of FIG. 1;

CPC F23Q 2/36; H01M 8/04208

FIG. 3 illustrates a back view of the fuel cartridge of FIG. 1;

See application file for complete search history.

FIG. 4 illustrates a right side view the fuel cartridge of FIG. 1;

(56) **References Cited**

FIG. 5 illustrates a left side view of the fuel cartridge of FIG. 1;

U.S. PATENT DOCUMENTS

FIG. 6 illustrates a top view of the fuel cartridge of FIG. 1; and,

FIG. 7 illustrates a bottom view of the fuel cartridge of FIG. 1.

The broken lines are included for the purpose of illustrating unclaimed environmental portions of the fuel cartridge and form no part of the claimed design; the dash-dot-dash lines represent boundaries of the claimed design and form no part thereof.
